UNITED STATES PATENT OFFICE.

ELIAS MARSHALL, OF BOSTON, MASSACHUSETTS.

INDICATOR FOR ELEVATORS.

SPECIFICATION forming part of Letters Patent No. 349,729, dated September 28, 1886.

Application filed February 8, 1886. Serial No. 191,262. (No model.)

To all whom it may concern:

Be it known that I, ELIAS MARSHALL, of Boston, in the county of Suffolk, of the Commonwealth of Massachusetts, have invented 5 a new and useful Improvement in Altitude Indicators for Elevators Used in Buildings for Transporting Persons or Goods from Story to Story thereof; and I do hereby declare the same to be described in the following specification and represented in the accompanying drawings, of which—

Figure 1 is a view, partly in vertical section, of an elevator and parts adjacent thereto provided with my invention. Fig. 2 is a 15 vertical section of the air-compressor, and Fig. 3 is a similar section of one of the story-gages hereinafter described.

In such drawings, A denotes one wall of an elevator shaft or well, and B, C, and D the 20 floors of the stories next thereto, the lift or elevator being represented at E as at its highest altitude. From the said elevator a rope, a, winds about and is secured to a drum, b, upon whose shaft is a gear, c, that engages 25 with a train of gears, d, e, f, g, and g', the last of which meshes into a toothed rack, h, extending down from the air-compressor F, arranged as represented. The said air-compressor consists of two straight tubular vessels, i and k, the lower of which, closed at the 30 bottom and open at the top, receives within it the upper one, which, closed at top and open at bottom, is fitted within the said lower vessel, so that the latter may slide air-tight thereupon. The vessel i is to have within it a 35 charge, l, of mercury or some other proper fluid, and is to be movable vertically upon the vessel k, which is to be supposed to be stationary or fixed in position. A pipe, m, 40 opening out of the vessel k, at its top communicates with an ordinary pressure-gage, G, there being to the said pipe a stop-cock, n, to cut off the passage of air into the gage as occasion may require. Furthermore, there 45 opens out of the pipe m another pipe, o, provided at its upper part with a stop-cock, p. The said pipe o descends and communicates by a series of branch pipes, q, with several mercurial or spirit gages, H, one of which is 50 in each story of the building. Each of the said gages H is to have on its glass column r, or aside thereof, a scale, s, of a suitable kind

to indicate different altitudes of the elevator, or when it may be at any one of the stories of the building. This scale is shown in Fig. 55 3 by the numerals 1, 2, 3, 4, and 5 opposite to marks or dots made on the outer tube. Each gage H has a closed reservoir, t, to contain the mercury or fluid that by the pressure of the air in the reservoir is to be forced therefrom through a tube, u, into the internal glass tube, v, of the gage.

While the elevator or lift may be descending, the rack h will be moving downward, and as a consequence the portion i of the air-compressor will likewise be in movement downward, and will carry with it the liquid charge thereof, and thus relieve the pressure on the air within the pipes and allow the liquid to fall simultaneously in all the pressure-gages, 65 70 and in so doing will cause them to indicate the altitude of the elevator E, or whatever story of the building it may be at during its descent. In a rise of the elevator the vessel i will be elevated, so as to create in the vessel 75 k a compression of the air thereof and in the pipes leading from it to the gages. Such gages will then be caused to indicate the altitude of the elevator or the floor that from time to time it may reach, so that a person in any 80 story of the building, by looking at the gage therein, can determine the position or height of the elevator.

For each of the columnar gages H an ordinary pressure-gage provided with a dial and 85 an index pointer or hand to revolve thereon may be substituted, such dial having on it degrees or marks to denote the altitudes of the elevator.

What I have herein termed the "lift" or 90 "elevator" is frequently called the "car," the appellation "elevator" being in such case applied to such car and the machine for operating it.

I am aware of the elevator-indicator described and represented in the United States Patent No. 327,075, in which there is to the car a tank containing water, and from such tank a flexible pipe descends, all of which has to be lifted by the car in ascending. In my 95 100 indicator the air-compressor is stationary and separate from and not movable with the car, and, besides, I have no flexible pipe to rise or be drawn up with the car, nor any pipe in

the form of a loop to connect with such flexible pipe.

I claim—

5 The combination of the air-compressor and its operative mechanism, substantially as described, arranged out of and above the lift or elevator, and stationary relatively thereto, as explained, with such lift or elevator, the series of pressure-gages arranged in the different

stories of a building, and connected with such air-compressor by one or more pipes, all being essentially and to operate as and for the purpose set forth.

ELIAS MARSHALL.
